UNITED STATES PATENT OFFICE.

GEORGE D. PARKER, OF RIVERSIDE, CALIFORNIA.

FRUIT-GRADER.

1,149,402.

Specification of Letters Patent.

Patented Aug. 10, 1915.

Application filed July 21, 1914. Serial No. 852,250.

To all whom it may concern:

Be it known that I, GEORGE D. PARKER, a citizen of the United States, residing at Riverside, in the county of Riverside and State of California, have invented certain new and useful Improvements in Fruit-graders, of which the following is a specification.

The present invention relates to improvements in fruit graders, and particularly to a type of grader adapted for grading olives as to size.

The invention has for its principal objects to provide a fruit grader of the above type which occupies a minimum space and which is capable of separating the fruit to be treated into a number of grades; one in which the separated grades of fruit are conveyed to separate places of deposit and one in which the size of the separated grades of fruit may be varied.

With the above mentioned and other objects in view, the invention consists in the novel construction and combination of parts hereinafter described, illustrated in the accompanying drawings and pointed out in the claims hereto appended; it being understood that various changes in the form, proportion, size and minor details of construction within the scope of the appended claims may be resorted to without departing from the spirit or sacrificing any of the advantages of the invention.

To more fully comprehend the invention, reference is directed to the accompanying drawings, wherein—

Figure 1 is a view in side elevation of my invention, disclosing the superimposed oppositely inclined grading rolls and the bins and conveyors beneath the same. Fig. 2 is a broken end elevation taken on line 2—2 of Fig. 1. Fig. 3 is a top plan view of the invention with a portion of certain of the directing members broken away to more fully disclose the sizing boards.

Referring more particularly to the drawings, wherein like characters of reference designate corresponding parts throughout the several views, the numerals 1 designate suitable base members on which are mounted the corner standards 2 connected at their top by the top members 3 and the whole forming a supporting frame.

Rotatably mounted at their opposite ends in bearings 4 carried by the supporting

frame are the parallel spaced grading rolls 5, arranged in sets A and B, one above the other, and said sets of grading rolls are downwardly inclined in a direction opposite to each other. The upper set of rolls A are driven at their upper ends in the direction of the arrow through gear connections with a drive shaft 6 rotatably mounted in bearings 6¹ and driven by power transmitted to the belt pulley 7 carried thereby. A shaft 8 rotatably mounted in bearings 9 has gear connection with the upper ends of the rolls 5 of the lower set of rolls B and is rotated through a chain connection 10 operated by the drive shaft 6 to rotate said lower set of rolls in the direction of the arrow.

Suitable grading members 11 extend longitudinally of and are positioned between the grading rolls 5 of each set and said members are arranged in sets with each member of a length approximately one-half of the length of the rolls so that a plurality of sizes of fruit may be graded by one roll. The grading members are adjustably secured by bolts 11¹ to the set supporting strips 12 which are adjustably supported at their ends on side members 12¹.

A suitable directing member 13 extends longitudinally of each grading roll directly above the axis thereof, and said members are inclined transversely of the rolls for directing the fruit delivered to the rolls toward the sizing member associated therewith, the fruit if it be of a size sufficiently small passes between the roll and grading member, but if too large to pass between the same, rolls longitudinally of the roll. Fruit to be treated is conveyed toward the upper end of the rolls 5 forming the upper set A by the endless conveyer belt 14 operating around a drum 15, and said belt discharges onto an inclined chute 16 which directs the fruit onto the grading rolls.

Positioned below each set of grading rolls 5 are suitable bins 17, each adapted to receive the fruit graded by the respective sets of grading members. The bins are formed with side walls 18 which slope downwardly toward each other, and each bin is formed with an outlet opening 19.

Positioned below the respective outlets 19, to receive the graded fruit passing therefrom, are the endless conveyer belts 20, 21, 22 and 23, operating at their opposite ends over the respective pairs of drums 25, 26, 27 and 28

carried by suitable shafts 29, 30, 31 and 32 journaled in bearings carried by the supporting frame. The drums are driven to operate the belts in the direction of the arrow by the following mechanism.

A shaft 33 supported by brackets 34 is driven by the drive shaft 6 and has gear connection with the shaft 29 supporting one of the drums 25. The shaft 29 drives a counter-shaft 29', as shown in Fig. 1, and said counter-shaft has gear connections 35, 36 and 37 with the respective shafts 30, 31 and 32.

It will be apparent that the different sizes of fruit obtained will each be conveyed from the bins by a separate conveyer, and suitable receptacles 38 receive the fruit discharged from the ends of the conveyers through the chutes 39, one of which is associated with each receptacle and extends to one of said conveyer belts.

Should the fruit passing along the set of grading rolls A be of a size too large to pass between the rolls and the grading members associated therewith, the same will pass from the ends of rolls 5 forming set A, and will be directed by the guides onto the upper ends of the rolls 5 forming set B. If the fruit deposited on set B is too large to pass between the rolls of set B and the grading members associated therewith, which are adjusted to a position a greater distance from the rolls than those of set A, the same will pass from the lower ends of the rolls of set B into a suitable receptacle 40.

I have provided an apparatus which is capable of separating a quantity of fruit into a plurality of grades or sizes each grade or size being conveyed therefrom by an independent means, one occupying but little space, one in which the grading members are independently adjustable on the supporting members, and in which the supporting members are independently adjustable relative to the supporting frame, so that a small quantity of fruit slightly larger than the general run of fruit into a certain bin may be directed thereto should it be desirable to do so.

Having thus described my invention what I claim as new and desire to protect by Letters Patent is:—

1. An apparatus of the described character, the same comprising a set of downwardly inclined parallel spaced separated grading rolls, a grading plate extending longitudinally of each roll and therebetween, so as to overlie one side thereof, said grading members being independently adjustable, and a support for a plurality of grading members, said support being adjustable to permit simultaneous adjustment of said plurality of grading members.

2. An apparatus of the described character, the same comprising downwardly inclined parallel spaced grading rolls, a stationary directing member extending longitudinally above each of said rolls, a plurality of grading plates extending longitudinally of and between each of said rolls and arranged in a set, means whereby the individual grading plates may be adjusted relative to said directing members and to each other, means for rotating said rolls, and means beneath said rolls for receiving the fruit separated by each set of grading members.

3. An apparatus of the described character, the same comprising a plurality of downwardly inclined parallel spaced grading rolls, a fruit directing member extending longitudinally above each of said rolls, said directing members inclining transversely with the lower edge thereof substantially in contact with the rolls, a plurality of grading plates extending longitudinally of and between each of said rolls and arranged in a set, said set of grading plates being adjustable relative to the grading rolls, each plate being adjustable independently of the other and independent of the directing members, means for feeding fruit to the upper ends of said rolls, means for rotating said rolls, and means beneath said rolls for receiving the fruit separated by each set of grading plates.

4. An apparatus of the described character, the same comprising a plurality of downwardly inclined parallel spaced grading rolls, a fruit directing member extending longitudinally above each of said rolls, a plurality of vertically extending grading plates extending longitudinally of and between each of said rolls and arranged in a set, said plates being independent of said directing member, said set of grading plates being adjustable independently of each other relative to said directing members and grading rolls, means for feeding fruit to the upper ends of said rolls, a conveyer for receiving the fruit separated by each set of grading plates, and a common means for rotating said grading rolls and for operating said conveyers.

5. An apparatus of the character described, the same comprising a plurality of downwardly inclined parallel spaced grading rolls, a normally stationary fruit directing member extending longitudinally above each of said rolls, and inclined with the lower edge substantially in contact with the periphery of the rolls, a vertically disposed grading plate arranged to the side of each roll and extending thereabove, and having an offset flange at the upper edge thereof, a supporting member extending transversely relative to said grading mem-

bers, and an adjustable connection between said supporting member and grading members.

6. An apparatus of the character described, the same comprising a plurality of downwardly inclined parallel spaced grading rolls, a normally stationary fruit directing member extending longitudinally above each of said rolls and inclined with the lower edge substantially in contact with the periphery of the rolls, a vertically disposed grading plate arranged to the side of each roll and extending thereabove, and having an offset flange at the upper edge thereof, a supporting member extending trans-

versely relative to said grading members, an adjustable connection between said supporting member and grading members, and means for adjustably supporting the last mentioned support whereby a plurality of 20 said grader members may be simultaneously adjusted with respect to the rolls.

In testimony whereof I have signed my name to this specification in the presence of two subscribing witnesses.

GEORGE D. PARKER.
